STOMA RECEIVER

Murle Perry, Minneapolis, Minn.

Application July 7, 1950, Serial No. 172,520

10 Claims. (Cl. 128—283)

1

This invention relates to stoma receivers, sometimes referred to as colostomy appliances.

It is one of the objects of this invention to provide a novel and improved stoma receiver which can be applied to the body to fit over a stoma and receive the discharge therefrom and which may be held on the body as by a body encircling belt and which can be adjusted relative to the belt so as to properly fit the contour of the body without applying undue pressure at any one point thereto.

Another object of the invention is to provide a stoma receiver including a container in the form of a flexible bag, a retaining ring which may be employed for clamping the mouth of the container against the body, and means for holding the ring against the body, the ring being capable of being tilted outwardly from the body to permit removal of the container through the opening in the ring.

A further object is to provide a novel and simple guard which may be removably applied to the retaining ring referred to in the last paragraph above so as to protect the mouth of the flexible container from collapse thereof when clothing is being worn and which can be readily removed so as to permit the stoma receiver to be used without the guard at night when outer clothing is not being worn.

Yet another object is to provide a belt keeper which can be adjustably mounted at different vertical heights on the retainer last above referred to, the keeper being employed to attach to a body encircling belt, an adjustment of the keeper in a vertical direction being desirable to apply pressure from the belt against the retaining ring in accordance with the peculiarities of the contour of the body of the person wearing the stoma receiver.

Still another object is to provide a novel and improved flexible means for attaching a stoma receiver to the body directly.

These and other objects and advantages of the invention will more fully appear from the following description made in connection with the accompanying drawings, wherein like reference characters refer to the same or similar parts throughout the several views, and in which

Fig. 1 is an exploded view showing different parts of a stoma receiver embodying the present invention;

Fig. 2 is a vertical section of the stoma receiver incorporating the parts shown in Fig. 1, showing these parts as they will appear when assembled for attachment to the body;

Fig. 3 is a vertical section similar to Fig. 2 but wherein a different type of apertured head than as shown in Figs. 1 and 2 is employed and the parts for directly cementing the device to the body are not used;

Fig. 4 is a plan view looking toward the upper end of the guard that is used;

Fig. 5 is a vertical section in perspective of a dome-like container that may be at times employed with the stoma receiver as when the bag-like container has been removed for emptying and cleaning;

Fig. 6 is a view showing the stoma receiver when the parts are assembled as shown in Fig. 2 as applied to the body, a single belt being employed and the belt running through the belt keeper which is secured to the guard;

Fig. 7 is a view showing the stoma receiver assembled as shown in Fig. 3 and applied to the body, the guard, however, not being attached and a single belt being employed for holding the stoma receiver on the body and this belt being attached to the retaining ring;

Fig. 8 is a view similar to Fig. 7 but showing the use of a double belt for attachment of the stoma receiver to the body;

Fig. 9 is a view generally similar to Fig. 7 but showing the dome-like container illustrated in Fig. 5 applied for use when the bag-like container shown in Figs. 6, 7 and 8 has been removed; and

Fig. 10 is a view showing the stoma receiver applied to the body assembled as shown in Fig. 3 but with a belt member of special construction running through the keeper attached to the guard of the device, the belt member being held in place by a double waist-encircling belt.

The stoma receiver includes a container holding ring 11 having a rather large central opening, the walls of which taper from the inner or body side of the ring toward the outer side of the ring, i. e., the opening in the ring is of slightly less diameter at its outer side than at its inner side. A flexible bag-like container 12 is also provided and this bag has a channel-shaped ring-like mouth 12a within which the ring 11 is received, the mouth 12a being vertically disposed. The bag-like container 12 will preferably be made of some flexible resilient material such as rubber or partially resilient plastic, and the channel-shaped mouth 12a will be capable of being stretched to snap over the ring 11. The mouth end of the bag is somewhat narrower than the body portion 12b of the bag and the body portion is preferably provided with vertical fluting so as to be readily expandible for the purpose of carrying a large

quantity of material. Below the body 12b the bag again narrows to form an outlet neck 12c which is open at its lower end. To close the lower end of the outlet neck 12c this neck is carried in a bight over a hollow, rather heavy rubber tube 13 and a metal channel 14 is then slipped over the said bight so that the tube 13 and bight are held within the channel.

A retaining ring 15 formed of rigid material is employed as a backing ring outwardly of the container holding ring 11 to press the ring 11 and the bag mouth 12a toward the body of the wearer. The retaining ring 15 has a rather large opening therethrough and when the retaining ring is tilted outwardly at its upper portions from the container holding ring 11 as shown in the exploded view Fig. 1, it is possible by raising the holding ring 11 and the bag-like container 12 to draw the body 12b of the bag-like container through the retaining ring 15, even though the bag is filled, for the purpose of emptying and cleaning the bag container 12. This permits the bag-like container 12 to be removed from the body without complete removal of the retaining ring 15 as will be more fully explained hereafter. The retaining ring 15 has an outer circumferential, outwardly extending grooved flange 15a for a purpose presently to appear. Also, this ring 15 carries on its outer face at its sides at different levels a plurality of outwardly projecting knobs 16 for the purpose of permitting the attachment of a belt or belts to this retaining ring 15.

There is also provided a guard 17, this guard including a body portion 17a formed preferably of metal or rigid material and having inturned edges which are rolled to receive a wire 18. This wire includes lower inwardly extending spring hook ends 18a and an upper, offset, arcuate, inwardly extending hook portion 18b. The guard 17 is adapted to be releasably attached to the retaining ring 15 by first engaging the upper arcuate hook portion 18b within the upper portion of the groove of the grooved flange 15a of the retaining ring and thereafter springing the lower hook ends 18a inwardly and catching the outturned portions of these hook ends, also, in portions of the groove of the flange 15a of the ring 15. When so attached to the ring 15, as for example as shown in Figs. 2, 3, 6 and 10, the body 17a of the guard is outwardly spaced from the upper mouth portion of the bag-like container 12 and it prevents collapse of the mouth portion of the bag container so that there will be freedom for the passage of material through the neck of the bag-like container into the body portion 12b thereof at all times from the stoma. At times it is desirable to use the stoma receiver without the guard 17 and, of course, the guard can be very quickly and easily removed from the retaining ring 15 by disengagement of the hooks 18a and 18b from the grooved flange 15a of the ring 15.

For use in slidably attaching a belt to the guard 17 there is provided a circular belt keeper 19, this belt keeper having opposed inturned tabs through which a belt may be slid. This keeper carries a central inwardly projecting stud 20 in the form of a half-snap fastener and this stud projects through a central opening in the belt keeper and is adapted to be received in any one of a number of vertically spaced openings 21 formed in the body 17a of the guard 17. To hold the stud 20 in place within the selected opening 21, there is provided a cooperating female half-snap fastener 22 which will be placed

at the inner side of the body 17a of the guard, and this half-snap fastener 22 may be releasably engaged with the half-snap fastener shaped stud 20. Preferably, the half-snap fastener 22 is attached to a rubber disc 23 which serves to protect the upper portion of the bag 12 from injury by the half-snap fastener 22. In addition to forming a part of the connection for connecting the belt keeper 19 to the body 17a of the guard 17, the stud 20 also acts as a pivot permitting turning movement of the belt keeper 19 relative to the guard 17, thereby permitting a belt running through the keeper to be disposed at any desired angle relative to the guard and at the most comfortable angle to position the stoma receiver properly to fit the contour of the body of the wearer.

As the stoma receiver is shown in Figs. 1 and 2, and as it applied to the body as shown in Fig. 6, the stoma receiver includes an apertured head 24 having an outer tapered flange 24a to snugly and tightly but removably fit within the tapered opening of the container holding ring 11. The inner surface of the apertured head 24 is preferably somewhat dome-shaped and this head is equipped with an outwardly projecting grooved flange 24b. Also, as the device is shown in Figs. 1 and 2, and as it will be employed as shown in Fig. 6, the device includes a flexible disc 25 preferably made of rubber or flexible plastic which may be cemented directly to the body of the wearer, the cement, of course, being applied to the inner side of the disc 25. This disc 25 has an aperture 25a through which the stoma will be extended. Vulcanized to the outer side of the disc 25 is a flexible tube 26 preferably made of rubber or similar material and this tube is extended inwardly through the aperture of the head 24. It is provided preferably with a bead at its outer end and the beaded outer end of the said tube is carried over the grooved flange 24b of the head 24 and snapped in place within the groove thereof. The disc 25 is thus attached to the head 24 by the tube 26 and as this tube is flexible, the head 24 may have limited movement relative to the disc 25 and may be somewhat angularly disposed in respect to the general plane of the disc 25. It will also be noted that the tube 26 is vulcanized to the disc 25 outwardly from the opening 25a in the disc and, hence, the movement of the tube 26 is possible without contacting the stoma which projects through the opening 25a and tilting action of the head 24 may take place without contacting the stoma. The disc 25, being formed of flexible material, may conform closely to irregularities in the body of the wearer and will yield with movements of the body.

In place of the apertured head 24, disc 25 and tube 26, an apertured head 27 as shown in Fig. 3 and as employed as the device is shown as worn on the body in Figs. 7, 8, 9 and 10, may be used. This head 27 is provided with a flange 27a adjacent its circumferential edge at its inner side and the circumferential edge of the head 27 is tapered to fit the container holding ring 11. The aperture in the head 27 may be made of different sizes to fit requirements of the particular patient for the stoma to properly be received through this aperture. When the device is used as shown assembled in Fig. 3, an apertured pad 28 is normally employed between the body and the head 27, this pad being made of cellulose material and being replaceable from time to time at but slight expense.

The stoma receiver may be held onto the body in different manners by different types of belts. In Fig. 6 the stoma receiver is held in place by an adjustable body encircling belt 29 which is slidably received through the keeper 19. In Fig. 7 an adjustable body encircling belt 30 is employed for holding the stoma receiver onto the body, this belt being equipped at its ends with eye-like fasteners 31 which may be engaged respectively with opposing nobs 16 carried by the retaining ring 15 at desired levels. By engaging these eyes 31 with nobs 16 at higher or lower levels, the pressure applied by the belt against the retaining ring 15 holding the device against the body may be varied to suit the peculiarities of the contour of the particular person wearing the stoma receiver. In Fig. 8 there is shown a double belt 32 having at each end two sets of tabs to which non-engaging eyes 33 are secured. With this double belt, the pressure exerted by the belt may be distributed onto the retaining ring 15 at four points rather than two points, and by attaching the eyes 33 to the proper nobs 16 at the right levels the belt may be adjusted to the peculiarities of the body of the wearer.

In Fig. 10 the belt 32 carrying the nob-engaging eyes 33 is employed along with a belt section 34 having at its end portions nobs 35 with which the eyes 33 may be engaged, this belt section 34 having a central strap-like portion 34a which may be slidably received within the keeper 19 of the stoma receiver.

There is also provided with the stoma receiver a domed container 36 shown in Fig. 5 and in Fig. 9 which may be substituted for the bag-like receiver 12 on occasion. This dome-like receiver 36 will preferably be made of clear plastic and it is equipped with an outer flange against which the retaining ring 15 may bear, the dome portion projecting outwardly through the opening in this ring when this particular container 36 is being worn. This dome container may be used temporarily after the bag-like container 12 has been removed and while it is being emptied and cleaned prior to replacement. Also, at certain times it may be desirable to employ the dome container 36 in place of the bag-like container 12. It is, of course, unnecessary to employ the guard 17 when the dome-like container 36 is being worn.

Assuming that the parts of the device are assembled as shown in either Fig. 2 or Fig. 3 and that the device is being worn, when it becomes desirable to remove the bag-like container 12 for emptying or cleaning, this can be readily accomplished. If the guard 17 is being employed this guard can be easily removed, whereupon the retaining ring 15 may be tilted outwardly at its upper portion and the portion of the bag below the retaining ring 15 may then be drawn upwardly through the ring, whereupon it can be emptied and cleaned and replaced. In the meantime, the dome-like container 36 may be applied to the retaining ring 15 and if either the belt 30 is employed or the double belt 32 is employed, the bag 12 may be removed without unfastening either the belt 30 or the belt 32 from the nobs 16 attached to the retaining ring 15. These belts 30 and 32 have enough give to permit tilting of the retaining ring 15 as indicated in Fig. 1 to permit removal of the bag 12. Of course, if the belt 29 is employed or if the belt 32 is employed with the belt section 34, it becomes almost necessary to remove these belts from the keeper 19.

and raise the belts above the device prior to the time the guard 17 is removed in order to permit of the removal of the bag-like container 12.

It will be seen that a highly effective though simple stoma receiver has been provided.

It will, of course, be understood that various changes may be made in the form, details, arrangement and proportions of the various parts without departure from the scope of the present invention, which, generally stated, consists in the matter shown, and described, and set forth in the appended claims.

What I claim is:

1. A stoma receiver comprising a container holding ring, a container having a flexible mouth carried by said ring, said container receiving from a stoma through the opening in said ring, a retaining ring disconnected from said holding ring and container and normally backing said container holding ring, a guard removably attachable to the outer side of said retaining ring, said guard having a body portion spaced outwardly from said retaining ring when the guard is attached thereto to prevent collapse of the mouth of said container, said guard having a plurality of vertically spaced apertures therethrough, a belt keeper, a half-snap fastener carried by said keeper and adapted to be mounted in any one of said apertures, a half-snap fastener for cooperative engagement with said first mentioned half-snap fastener at the inner side of said keeper, and a belt member slidably receivable in said keeper.

2. The structure defined in claim 1, a belt retaining member at the ends of said belt member and a body encircling belt attachable to said belt retaining member.

3. A stoma receiver comprising a flexible apertured disc adapted to be cemented to the body of a wearer to receive a stoma through the aperture thereof, a flexible resilient tubular extension projecting outwardly from the outer side of said disc, an apertured head having an outwardly projecting grooved flange at its outer side, said tubular extension being adapted to be projected through the aperture in said head and to be engaged by said grooved flange, a container holding ring within which said apertured head is received, and a container having a mouth attached to said container holding ring.

4. The structure defined in claim 3, a retaining ring disconnected from said holding ring and container and normally backing said container holding ring, a body encircling belt, and means for removably attaching said belt to said retaining ring.

5. The structure defined in claim 3, a retaining ring disconnected from said holding ring and container and normally backing said container holding ring, said container having a flexible mouth, a guard removably attachable to the outer side of said retaining ring to overlie the mouth of said container, said guard having a body portion spaced outwardly from said retaining ring when the guard is attached thereto, a body encircling belt and means for attaching said belt to the structure formed by said guard and retaining ring.

6. A stoma receiver comprising a container holding ring, a container having a flexible mouth attached to said holding ring and adapted to receive from a stoma through the opening in said ring, a retaining ring disconnected from said holding ring and the container attached thereto and normally backing said container-holding

ring, said retaining ring having an outwardly extending grooved flange, a guard having a plurality of at least slightly resilient attachment elements adapted to be received in substantially opposed portions of said grooved flange to releasably hold said guard in overlying relation to the mouth of the container and thereby prevent inwardly directed pressure from collapsing said container mouth, a belt-keeper having an attachment element on the inner side thereof, cooperating attachment means on the outer side of said guard for permitting vertical adjustment of said keeper on said guard, and a body-encircling belt adapted to be carried through said keeper.

7. A stoma receiver comprising a flexible apertured disc adapted to be cemented directly to the body of the wearer to receive a stoma through the aperture thereof, a flexible resilient tubular extension projecting outwardly from the outer side of said disc, an apertured head having an outwardly projecting grooved flange, said tubular extension being adapted to be projected through said aperture in said head with the outer portion thereof engaged by said grooved flange, means for sealingly attaching the mouth of a container to said apertured head, and means for attaching said container and said head to the body of a wearer.

8. The structure of claim 7 wherein the means for sealingly attaching the mouth of the container to the apertured head includes a backing ring which fits about the container mouth and wherein the means for attaching the container and the head to the body of a wearer includes a belt and a vertically adjustable connection between the belt and the backing ring.

9. The structure of claim 7 wherein the means for sealingly attaching the mouth of the con-

8
tainer to the apertured head includes a backing ring which fits about the container mouth and wherein the means for attaching the container and the head to the body of a wearer includes a belt, and a vertically adjustable connection between the belt and the backing ring consisting of a guard carried by and projecting outwardly from the ring and a member detachably connected with the outwardly projecting guard and shiftable vertically to adjusted positions.

10. The structure of claim 7 wherein the means for sealingly attaching the mouth of the container to the apertured head includes a backing ring which fits about the container mouth and wherein the means for attaching the container and the head to the body of a wearer includes a belt, and a vertically adjustable connection between the belt and the backing ring consisting of sets of knobs projecting outwardly from the ring at opposite sides thereof, the knobs of each set being vertically spaced from each other and each in the same horizontal plane as the corresponding knob of the other set, and clips carried by said belt and detachably engaged with knobs at opposite sides of the ring for vertical adjustment of the ring relative to the belt.
